United States Patent Office

Des. 186,105
Patented Sept. 15, 1959

186,105

AIRCRAFT PASSENGER SEAT

Clifford E. Dietz, San Diego, and Wilfred H. Brehaut, Jr.,
Poway, Calif., assignors to General Dynamics Corpora-
tion, San Diego, Calif., a corporation of Delaware

Application May 20, 1959, Serial No. 55,999

Term of patent 14 years

(Cl. D15—8)

FIG. 1

Des. 186,105

PAGE 2

FIG. 2

Figure 1 is a front perspective view of the aircraft passenger seat, illustrating our new design; and

Figure 2 is a rear perspective view of the seat taken from the same side of the seat as that shown in Figure 1.

We claim:

The ornamental design for an aircraft passenger seat, substantially as shown.
